UNITED STATES PATENT OFFICE.

EDWARD KENER, JR., OF BUFFALO, NEW YORK.

VALVE.

Application filed April 2, 1926. Serial No. 99,389.

This invention relates to a valve, and is more particularly intended to be used for controlling the flow of fuel gas in an incinerator. In the form of incinerators in which this valve is intended to be used, the same is arranged on the exterior of the incinerator and is adapted to be operated manually, and means are also provided for automatically closing the valve and shutting off the flow of fuel gas when the pile of refuse in the incinerator is completely consumed.

It has been found that where a regulating gas valve was provided in an incinerator, there was a tendency on the part of the operator to turn the gas down, and operate the incinerator with an insufficient supply of gas especially when the operator was leaving the house for a length of time. While a complete reduction of the refuse was effected, this operation resulted in an incomplete combustion of the refuse and the consequent production of obnoxious unconsumed gases and fumes which were carried to the exterior of the building and produced a disagreeable odor around the same.

The principal object of this invention therefore is to provide a valve which is either completely open or completely closed, and which when completely opened is locked in such position until tripped automatically or by hand.

Further objects are to provide such a valve which is simple and inexpensive in operation and not liable to get out of order through constant use.

In the accompanying drawings:

Figure 1 is a top plan view of the valve.

Figure 2 is a vertical longitudinal sectional view of the same.

Figure 3 is a fragmentary view showing the means for limiting the upward movement of the locking bar.

Figure 4 is a front end view of the valve.

Figure 5 is a side elevation of the same.

Similar characters of reference indicate like parts in each of the views.

The valve housing is composed of two sections 6 and 7 which are joined by a screw connection 8. The rear section 7 is provided with an interior wall 9 forming an outlet chamber 10 in the rear of this section, and this wall is provided with an opening 11 around which is formed a forwardly facing conical valve seat 12. An outlet 13 is provided in rear of the wall 9 and is adapted

to be attached to the pipe (not shown) leading to the gas burner, and a laterally projecting inlet 14 is provided in front of the wall 9 and is adapted to be secured to the gas manifold (not shown) in any suitable manner.

A longitudinally movable plunger 15 is slidably mounted in the front end of the front section and at its rear end is provided with a conical head 16 adapted to engage the conical valve seat and cut off the flow of gas through the valve. The plunger is normally held in its rearward or closed position by a return spring 17 surrounding the inner end of the plunger and interposed between the housing and the head 16.

The plunger is drawn forwardly by an upright operating lever 18 which is pivotally secured at its center to the outer end of the plunger and at its lower end is pivotally secured to a forwardly projecting lug 19 formed integrally with the front section 6 of the valve housing. The upper end of the operating lever is suitably shaped to provide a convenient handle for the operation of the valve and the lower end 20 is in the form of a blade which is received in longitudinal slots 21 and 22 provided in the outer end of the plunger and the lug 19, respectively, and held therein by transverse pivot pins 23 and 24. The blade 20 of the operating lever is formed to permit the plunger to be drawn outwardly and its lower rear edge 25 is curved and adapted to engage and bear against the bottom or rear end 26 of the slot 22 when the lever is moved forwardly thereby relieving and preventing wear on the pivot pin 24 when the valve is being opened.

The movement of the pivot pins 23 and 24 toward and from each other as the valve is closed and opened is permitted by providing a curved opening 27 in the lower end of the operating lever which is penetrated by the pivot pin 24 and thereby provides a sliding connection at this point. The opening is somewhat wider than the pivot pin thereby permitting the rear edge of the blade 20 to freely engage the bottom 26 of the slot 22 and is curved to conform to the movement of the lower end of the blade 105 relative to the pin 24, thereby insuring free movement of the operating lever.

In order to lock the plunger when the same is drawn to its fully opened position, and hold the valve open until released auto- 110

matically or manually, the plunger is provided with a recess 28 on its upper side which is arranged outside of the valve housing when the valve is fully opened and is adapted to receive the lower edge of the transverse locking bar 29.

- The locking bar rests against the forwardly facing flat side 30 of the valve housing, and is pivotally secured at 31 to a lateral extension 32 so as to be capable of swinging upwardly and downwardly. The free or outer end of the locking bar extends across the upper side of the plunger, and in the closed or inward position of the plunger 10 rests on the upper side thereof. When the plunger is drawn outwardly to its fully opened position, the locking bar drops by gravity into the recess 28 provided on the upper side of the plunger and prevents the 15 valve from closing until the locking bar is tripped. In order to prevent undue wear of the plunger at the front corner of the recess 28, a hardened pin 36 is set into the plunger at this point as shown in Figs. 1 and 2.
- 20 To prevent the locking bar 29 from being raised further than is necessary to free the plunger, the same is pivoted between an L-shaped support 33 and the extension 32, and the under side of the locking bar is recessed 25 to form a catch or stop 34 which is adapted to engage a corresponding stop face 35 on the support when the bar is raised and thereby limit the upward movement of the bar.

As a whole this valve is extremely simple 30 and durable in construction and is not liable to get out of order or wear unduly through constant use; it operates reliably to perform the function set forth and is not liable to become accidentally tripped or released.

40 I claim as my invention:

1. In a valve, a valve mechanism having a longitudinally movable operating plunger, said plunger having a recess on its upper side, a locking bar pivotally mounted to one 45 side of said plunger and extending transversely across the upper side thereof, the longitudinal edge of said locking bar being adapted to drop into engagement with said

recess and hold said plunger in one position, and the outer end of said locking bar being 50 formed to provide a handle whereby the locking bar is lifted to release said plunger.

2. A valve comprising a valve housing having a valve seat and an inlet and outlet arranged on opposite sides of said seat, a 55 longitudinally movable plunger mounted on said valve housing and adapted to engage said seat, a spring tending to hold said plunger in engagement with said seat, said plunger projecting outwardly from said casing and being provided on its upper side with a recess, and said casing being provided with an exterior transverse flat face adjacent said plunger, and a flat locking bar pivotally mounted on said face of the casing to one 60 side of said plunger and extending across the upper side thereof, said locking bar being adapted to drop into said recess and hold said plunger in an outward position, and the outer end of said locking bar being formed 65 to provide a handle whereby the locking bar is lifted to release said plunger.

3. A valve comprising a valve housing, a valve mechanism arranged in said housing and having a longitudinally movable actuating plunger projecting outwardly therefrom; means tending to hold said plunger in its inward position, means for drawing said plunger outwardly comprising an operating lever pivoted centrally to the outer end of 70 said plunger, and a lug projecting forwardly 80 from the lower end of said housing, the lower end of said lever being slidingly secured to said lug, and means for locking said plunger in its outward position comprising 85 a locking bar pivoted to said housing to one side of said plunger and extending across the upper side of said plunger, said plunger being provided with a recess on its upper side into which said locking bar is adapted to 90 drop when said plunger is in its outward position.

In testimony whereof I hereby affix my signature.

EDWARD KENER, JR.
